TURBINE FOR HOT DRIVING MEDIA

Alf Lysholm, Stockholm, Sweden, assignor to
 Aktiebolaget Milo, Stockholm, Sweden, a corporation of Sweden

Application March 6, 1934, Serial No. 714,227
 In Germany March 10, 1933

3 Claims. (Cl. 253—39)

The invention refers to turbines for hot driving media, and particularly to gas turbines.

One of the greatest difficulties in the construction of such turbines is the control over the high temperatures and the resulting stresses and alterations of the machine parts, particularly of the blade systems, coming into contact with the hot driving medium.

The invention particularly relates to such turbines, in which the blade carriers, which may be turbine disks or turbine rings, increase with respect to the diameter from the inlet to the outlet. Such turbines are the radial flow turbines, for example, especially the double rotation radial flow turbines in which the blade rings increase radially outwards from stage to stage, and furthermore, axial flow turbines, the disk diameters of which increase progressively from the point of inlet unto the outlet.

In turbines of this kind, the inlet takes place at the point of the smallest blade ring diameter or disk diameter. Here, the highest temperatures occur, however. By reason of this, the temperature stresses, particularly also the creeping, are here the highest, while these temperature stresses decrease considerably toward the outlet. On the other hand, the stresses referring to the strength of material which result from the centrifugal force upon rotation of the turbine, are considerably smaller on the inlet side of such turbines than in the stages of a greater diameter located adjacent to the outlet.

Accordingly, the blade systems will be differently strained by the temperature influences and the dynamic influences in the various stages of the blade systems. This, however, brings about difficulties as regards the construction, insofar as it should be aimed at in all stages to keep the clearance losses as small as possible. The varying stresses in the different stages will have an interfering effect, however.

In order to bring about an improvement here, it is suggested, according to the invention, to make the blade carriers of a small diameter operating in the range of the higher temperature out of a material which is less sensitive toward creeping, preferably austenite material of austenite structure, and the blade carriers of a greater diameter operating within the range of the lower temperatures out of a material of great strength, preferably martensite material.

For a better understanding of the nature of the invention, reference may be had to the accompanying drawings forming a part of this

specification and the following description thereof.

In the drawings:—

Fig. 1 represents diagrammatically the influence of the selection of materials for the turbine construction;

Fig. 2 shows a rotor of an axial flow turbine designed according to the invention;

Fig. 3 an axial flow turbine; and

Fig. 4 a radial flow turbine constructed according to the invention.

Fig. 1 shows a number of curves calculated for a creeping of 10,000 hours. Curve 1 gives 40% of the limit of the stretching strain of martensitic material, that is to say strains which in the construction of turbines generally are permitted as a basis for construction. It will be seen from the curve that the permissible stretching strain decreases with a rising temperature up to 430° C. from 37 to 28 kg./sq. mm. The influence of the creeping will be seen from curve 2, which shows that for martensitic material the permissible strain on the material decreases very considerably, owing to the creeping which occurs on a temperature rise from 430 to 500° C. Curve 3 shows 40% of the limit of the stretching strain of austenitic material, and curve 4 the influence of the creeping of this material.

The illustration thus shows that up to a temperature of 430° C. the creeping is of no consequence relatively to the stresses referring to the strength of the material through the dynamic forces, so that, consequently, martensitic material may be used altogether to advantage for temperatures below 430° C. The curve further shows, however, that this material becomes exceedingly sensitive on an increase of the temperature and is then no longer sufficient in higher temperature ranges, depending on the decisive influence of the creeping.

Fig. 1 thus shows it to be altogether possible to build turbines for high material temperatures, provided the selection of materials for the different temperature zones of the turbine is properly made with respect to the knowledge gained from the turbine.

For example, at a temperature of 700° C., that is to say 973° C. absolute, the strain must not exceed 5 kg./sq. mm. It can be shown, however, that both in the double rotation turbines, for instance according to the Ljungström system, and also in conical axial flow turbines, the strains may be kept below 3-4 kg./sq. mm., and that, consequently, turbine operation at a temperature of 700° C. is readily possible.

Fig. 2 shows diagrammatically the construction of a rotor of a conical axial flow turbine embodying the invention. The hollow rotor shaft 1 consists of martensitic material, which while being sensitive toward creeping possesses a comparatively great strength. The turbine disks 2, 3, 4 are made integral with said rotor shaft. The sensitivity of the martensitic material, of which this turbine part consists, is of no consequence in the 10 temperature range in which the rotors operate, the creeping being here without appreciable influence.

Thrust onto this hollow rotor shaft is a rotor part 5 carrying the disks 6, 7, 8. This part is 15 made from austenitic material, which is considerably less sensitive toward creeping than the martensitic material. Thus the division of the rotor into two construction zones made from different materials sufficiently answers the 20 strains occurring in the turbine both through the dynamic influences and through the temperature.

Fig. 3 shows the half of a conical axial flow 25 turbine constructed on the principles evolved in the foregoing. The turbine disks 9—14 operate in a high temperature range, within which the influence of the creeping is predominant. By reason of this, these disks are made from a material which is insensitive toward creeping, especially austenitic material. The line $x-x$ shows the temperature limit, above which the dynamic influences on the strength predominate, whereas the influences of the creeping are in the background. The turbine disks 15—19 situated 30 behind the line $x-x$ are thus made from a material of greater strength, which may be more sensitive toward creeping, such material being preferably a martensitic material.

The double rotation radial flow turbine according to Fig. 4 is built in the same manner, in principle, the line $x-x$ again indicating the temperature limit, for instance 500° C., below which the influence of the creeping and above which the dynamic strength influences predominate. Accordingly, the blade carriers 20—26 are made 40 from a material which is insensitive toward creeping, especially austenitic material, whereas the blade carriers 27—35 may be made from a material of greater strength, especially martensitic material, which may be more sensitive toward 45 creeping inasmuch as the lower temperatures and the higher rotational speeds predominate above the limit $x-x$.

The strengths and temperatures indicated in 50 Fig. 1 are average values only, which may change according to the material used; these values, however, hold good on an average for the construction materials generally used. From the 55 nature of the values of strength given in Fig. 1, it will be evident that the austenitic and martensitic materials hereinbefore referred to must be austenitic and martensitic steels of high quality, since such steels are known to be the only materials which can be of austenitic or of martensitic 60 nature and which can also have strength values of the order referred to. A substantial feature of the invention is, however, the idea to make the blade carriers of different materials and to locate the limit, at which the change of construction 65 materials takes place, where the influences of the

creeping and of the dynamic strength influences will predominate.

What I claim is:—

1. In turbine apparatus, a turbine rotor adapted to receive gaseous motive fluid at a temperature of at least 700° C. and to expand such motive fluid in a plurality of stages to a temperature at least as low as 400° C. through a path of flow from an inlet of relatively small diameter in a direction having a substantial component of flow in radially outward direction comprising a plurality of blade carriers of progressively increasing diameter from the inlet to the outlet end of said rotor, the blade carriers constituting the inlet portion of the rotor and adapted to carry blades for expansion of the motive fluid from its inlet temperature to a temperature of the order of 430° C. consisting of material of austenitic structure, and the blade carriers constituting the outlet portion of the rotor and adapted to carry the blades for expansion of the motive fluid from said temperature of the order of 430° C. to the exhaust temperature consisting of material of martensitic structure. 25

2. In turbine apparatus, a turbine rotor for expanding gaseous motive fluid admitted to the turbine at a temperature sufficiently high to produce creep, said rotor comprising a plurality of blade carriers for blades providing multiple stage expansion of motive fluid in the turbine in a path of flow from an inlet of relatively very small diameter to an outlet of relatively very large diameter as compared with the inlet diameter, the blade carriers of relatively small 30 diameter in the inlet portion of the rotor and within the temperature zone of the turbine where the temperature of the motive fluid during normal operation of the turbine causes creep producing conditions consisting of a suitable 35 turbine steel of austenitic structure and the blade carriers of relatively large diameter in the outlet portion of the rotor consisting of a suitable turbine steel of martensitic structure. 40

3. In turbine apparatus, a turbine rotor for expanding gaseous motive fluid admitted to the turbine at a temperature sufficiently high to produce creep, said rotor providing a path of flow for motive fluid having a relatively large component of flow in radially outward direction 45 from an inlet of relatively very small diameter and said rotor including a plurality of blade carriers the diameters of which progressively increase materially from the inlet end to the outlet end of the rotor, whereby the diameter of 50 the carrier at the outlet end of the rotor is several times the diameter of the carrier at the inlet end of the rotor, the carriers constituting the inlet portion of the rotor and located in a temperature zone where creep producing conditions are produced by the motive fluid in the normal operation of the turbine consisting of a suitable turbine steel of austenitic 55 structure and the blade carriers constituting the outlet portion of the rotor and located in a relatively much lower temperature zone consisting of a suitable turbine steel of martensitic structure. 60
